14 Claims. (Cl. 242—32)

1

This invention relates to winding machines and more particularly to winding machines in which a thread guide has a progressive advance, lengthwise of the winding bobbin, so that the zone of traverse is progressively advanced lengthwise, producing the typical filling wind.

United States Letters Patent No. 2,377,367, dated July 5, 1945, and No. 2,426,167, dated August 26, 1947, disclose winding machines in which a thread guide assembly is provided with a package feeler engageable with the thread on the winding bobbin and movable by such engagement into engagement with an element which operates as a profile element, to control the progression of the thread guide assembly in accordance with the wound body of thread on the bobbin attaining a desired diameter. In the mechanisms specifically shown in the aforesaid patents, the profile element which is engaged in this manner is formed as a rack shaped to determine a tapered base portion, followed by a cylindrical main body portion, of the winding package.

Growth of the body of wound thread on the bobbin to the predetermined desired diameter, at the particular stage of winding, forces the feeler outwardly away from the axis of the bobbin sufficiently far to engage the profile element and cause the necessary slight advance of the thread guide in its progressive movement.

In winding the typical filling wound bobbin in which the wound body of thread is formed with a tapered base, the package feeler must be capable of inward movement, toward the axis of the bobbin, into or approximately into actual contact with the bare bobbin so as to be capable of feeling a relatively small-diameter accumulation of thread during winding of the tapered base portion.

Subsequently, in winding the full-diameter cylindrical or straight-sided portion of the bobbin, the feeler must make contact with the growing surface of the bobbin at or very near the full diameter portion thereof, and by this engagement be moved into contact with the profile element or rack, to cause progression.

The feelers shown in the aforesaid patents thus are called on to engage the rack when contacting with thread very near to the surface of the bare bobbin while the initial layers of the ta-

pered base portion of the package are being wound, and are also called upon to engage the rack when contacting with thread at approximately the full diameter of the package while the cylindrical or straight-sided portion of the package is being wound. Accordingly feelers of this type have been arranged for yielding movement, against a restoring element such as a spring, from very close proximity to the bare bobbin outwardly into engagement with the rack at each reciprocating stroke of the thread guide, even during winding the main full-diameter body portion of thread.

It now appears that during winding of the full-diameter portion of the thread, this length of movement of the feeler is excessive, being considerably more than required in use of the present invention. The present invention reduces the length of movement of the feeler and thereby reduces the wear between the feeler and its guides and improves the smoothness of operation of the device.

It now further appears that during the winding of the full diameter portion it is possible and desirable to prevent the feeler from moving inwardly to or approximately to the bare bobbin, and to prevent the feeler from engaging the more centrally located portions of the growing conical nose of the thread package upon the bobbin. It will be understood that the growing conical nose of the thread package is not entirely smooth, and that the bobbin at times may be somewhat warped and run out of true, so that in moving outwardly in contact with the growing conical nose, a feeler may tend to bounce outwardly away from the bobbin, and thus prematurely engage the profile element, causing premature or excessive progression of the thread guide and accordingly a groove or vacant space in the surface of the wound yarn on the bobbin.

In the devices of the aforesaid patents it is possible to reduce such bouncing tendency by increasing the force of the spring that urges the feeler inwardly toward the bobbin. However, undue inward pressure of the feeler is undesirable, particularly in the case of synthetic yarns which may be injured by undue pressure or soft yarns into which the feeler may tend to dig.

Accordingly the present invention provides for the feeler to be moved inwardly into, or approxi-

mately into, contact with the bare bobbin for winding of the initial layers, but provides that in winding the full diameter portion of the bobbin the feeler shall not approach so closely to the bare portion of the bobbin but shall operate with a relatively short in and out movement and engage only with the outermost portion of the growing conical nose of the thread mass. Excess in and out movement of the feeler and unnecessary extent of area of contact of the feeler and the growing conical nose of the thread mass are both avoided, producing a smoother operating and longer wearing mechanism and less contact with the thread.

While the profile element is shown in the present application as formed in the simplest manner as a fixed rack adapted to react directly upon the thread guide assembly by engagement of a tooth of the rack with the feeler, and so progressively advance the thread guide assembly along a traverse rod, other more complicated provisions for advancing the thread guide assembly may be used. In any case the function of the profile element is, as will be obvious, to establish the shape of the package being wound, and to condition the progressive advance of the thread guide upon attainment of the desired diameter by the wound body of thread.

In the preferred construction illustrated in which the profile element is in the form of a toothed rack, it is particularly advantageous to provide, as hereinafter explained, for shifting the feeler to a position in which it will not be caught and detained by the inclined portion of such rack located adjacent to the base of the bobbin during return movement of the thread guide assembly toward the base or starting position.

Other objects of the invention and advantageous features will be apparent from this specification and its drawings in which the invention is explained by way of example.

In the accompanying drawings:

Fig. 1 is a plan view, with certain parts broken away and certain parts omitted, of a traveling spindle filling winding unit of the general type disclosed in the aforesaid patents, but having the present improvement applied thereto;

Fig. 2 is a fragmentary plan view of the thread guide assembly of Fig. 1;

Fig. 3 is a vertical sectional view on the line 3—3 of Fig. 1 with the feeler element engaged with the surface of the winding thread mass on the bobbin;

Fig. 4 is a view similar to Fig. 3 showing the feeler element free from the surface of the thread mass;

Fig. 5 is an elevation of the thread guide assembly as viewed from the left of Fig. 3;

Fig. 6 is a fragmentary plan view with parts of the winding unit broken away showing the winding unit engaged by the winding unit tending mechanism and showing the thread guide assembly as being moved to the right following discharge of the fully wound bobbin from the winding position;

Fig. 7 is a view similar to Fig. 6 showing the thread guide assembly as moved to its extreme right-hand position;

Fig. 8 is a view similar to Figs. 6 and 7, but on a larger scale, showing the thread guide assembly in two positions, first, in the course of movement to the left following the position of Fig. 7, and second, in its extreme left-hand position; and

Fig. 9 is a view similar to Fig. 8 showing the

winding unit as winding the tapered base portion of thread upon a new bobbin.

Although the invention is of general applicability to winding machines in which the thread guide has a progressive movement along the length of the winding package, the invention is herein shown as applied to a winding machine of this type in which a plurality of winding units travel in a closed path during the winding, as in the aforesaid Letters Patent. Thus the machine includes a plurality of winding units, indicated at 1, which are moved by a chain 4 in a closed path about the machine upon a track consisting of upper and lower rails, a portion of the upper rail 2 being shown in the drawings.

A winding bobbin B is received between an inner hollow driving head or center or chuck 30, driven by an individual electric motor 60, and an outer retractable center or chuck 31.

20 A traverse cam driven through worm gearing by the motor 60 rapidly reciprocates round traverse rod 20, constituting the driver for the thread guide, the stroke of reciprocation of the rod 20 being relatively short and only a fraction 25 of the length of the yarn package to be wound on the bobbin B.

The thread guide assembly 9 which is frictionally connected to the reciprocating traverse rod 20 is shown as including an upper plate 61 and a lower plate 62 connected by vertical end pieces 63, 64 of fiber-composition material which frictionally engage the reciprocating traverse rod 20. The thread guide assembly also includes a tubular element 65 of fiber-composition material wrapped around the traverse rod 20 and compressively held in frictional engagement therewith by an inwardly pressing spring jacket 66.

Thread T runs from the thread supply up through an outer eye 67 in the upper plate 61, thence over the plate 61 through an inner eye 68 and thence down through the eye 68 onto the winding bobbin.

A rearwardly extending portion of the upper plate 61 carries a guide block 70 which is slidably beneath a guide bar 72, preventing the thread guide assembly from rotating around the reciprocating traverse rod 20.

The lower plate 62 is provided with down-turned portions 62^a and 62^b which are recessed 50 to receive a slidable feeler indicated generally at 72. As in Patent No. 2,426,167 the feeler is yieldingly urged to the right and its inner end is adapted to engage the wound thread on the bobbin as the thread guide assembly moves toward the base end of the bobbin, the feeler being slidably by this contact so as to bring the outer or left end of the feeler in Fig. 3 into contact with one of the teeth of a fixed rack or ratchet bar 78 serving as a profile element. This engagement 55 detains the thread guide against movement toward the base of the winding bobbin, allowing the traverse rod 20 to shift slightly relative to the thread guide assembly, producing the desired progressive advance of the thread guide assembly 60 relative to the traverse rod and toward the tip end of the winding bobbin.

The left end portion 78^a of the rack 78 is tapered to cause the base end portion of the thread package to be similarly tapered. Thus the toothed surface of rack 78 lies closest to the axis of the winding bobbin at its left end and then progressively diverges from the axis throughout the tapered portion 78^a which corresponds to the tapered base end of the thread package, and thereafter continues parallel or approximately

parallel to the axis throughout the main portion of the rack, corresponding to the main cylindrical body portion of the thread package.

In the early stages of winding of the tapered base portion of the package the feeler must feel the wound thread at a point which is necessarily close to the bare bobbin, as shown in Fig. 9, and be moved by this contact with the thread into contact with the rack. However in winding the full-diameter portion of the package the feeler should detect the presence of wound thread at a considerably larger distance from the axis, that is, at or very near to the full diameter of the forming cylindrical main body portion of the package, as in Fig. 1, and here again be moved into contact with the rack.

Instead of being moved inwardly approximately to the bare bobbin, regardless of the intended diameter of the part of the package being wound, as in constructions having thread guide mechanisms similar to those of the aforesaid patents, the feeler of the present invention is moved hardly any closer to the axis of the bobbin than is required to disengage its outer end from the rack 78. Fig. 3 shows the feeler 75 moved by the thread into engagement with the rack 78 as the thread guide assembly moves in its short stroke toward the base end of the bobbin. In Fig. 4, which represents the same stage of winding, but with the thread guide assembly moved toward the tip end of the bobbin, and the feeler free from the surface of the wound thread, the feeler is only slightly nearer to the axis of winding than in Fig. 3. The full line position of the feeler 75 in Fig. 1 represents the left end of the short stroke of the thread guide assembly toward the base of the bobbin, and the broken line position of the feeler in Fig. 1 represents the right end of the short stroke of the thread guide assembly toward the tip of the bobbin and corresponding to Fig. 4.

Thus as the feeler is moved to greater distances from the axis of the bobbin, as in being moved outwardly in conformity to progression along the tapered base portion of the package, the point of nearest approach of the feeler is allowed to withdraw relative to the axis of the bobbin.

The preferred illustrated construction includes a displaceable connection between the feeler and a feeler-restoring member permitting the feeler to be displaced relatively to the feeler-restoring member upon increase in outward extent of movement of the feeler away from the axis of the bobbin. In Figs. 3, 4 and 5 a feeler-restoring member is shown as comprising a slotted cylindrical body 90 of fiber-composition material frictionally engaging the feeler 75 and compressively held in frictional engagement with the feeler 75 by an inwardly pressing spring jacket 91. The feeler-restoring member, as shown in Figs. 3 and 4 is slightly shorter than the distance between the downturned portions 62^a and 62^b between which it moves, so as to have only a short movement between these portions, and is continually urged toward the axis of the bobbin and away from the rack by a spring 95. The outer end of the spring 95 is secured to the thread guide assembly, for instance to the outer downturned flange 62^a, and the inner end of the spring extends into and is secured to the cylindrical member 90, urging it and the feeler toward the axis of the bobbin.

Thus the feeler-restoring member has a limited zone of action, in between the two downturned flanges 62^a and 62^b in which it exerts a restoring action upon the feeler tending to restore the

feeler toward the axis of the bobbin. The frictional connection between the feeler and the feeler-restoring member permits displacement of the feeler relatively to this zone of action, while maintaining the feeler continually under the influence of the feeler-restoring member.

Obviously other different specific forms of feeler-restoring members could be employed. The illustrated construction including the fiber-composition material 90 and spring jacket 91 is preferred because of the proven ability of similar elements 65 and 66 to give long service in connecting the thread guide assembly to the traverse rod 20.

Upon completion of the winding, the feeler will occupy a position similar to that shown in Fig. 4, relatively close to the portion of the rack 78 which corresponds to the full-diameter cylindrical portions of the bobbin, or perhaps even in contact with the rack as in Fig. 3 in case the short stroke of the thread guide assembly happens to stop at its end toward the base of the bobbin. In this latter case, the feeler will resume the position of Fig. 4 after the wound bobbin has been dropped out from between the centers or chucks 30 and 31.

Figs. 6, 7 and 8 show the winding unit after completion of the bobbin and after the outer center or chuck 31 has been retracted by engagement of a chuck-retracting crank arm 34 with a stationary cam 36, the wound bobbin, now below the level of the chucks 30 and 31 being omitted for clarity of illustration.

As in the aforesaid patents the thread guide assembly is returned back along the traverse rod 20, in a direction opposite to its progressive movement to a position near the base chuck 30 in connection with positioning the thread across this base chuck, for clamping of the thread between this chuck and the base of a new bobbin. With its feeler in a position such as shown in Fig. 4 the thread guide assembly could be shifted backwardly along the main portion of the rack 78 but the outer end of feeler 75 would catch upon the inwardly tapered portion 78^a of the rack. The feeler could be prevented from colliding with the teeth of the tapered portion 78^a of the rack upon this backward or return movement of the thread guide assembly toward the base chuck by employing the construction shown in Fig. 11 of Patent No. 2,426,167 to displace the rack, or at least the portion 78^a thereof, out of the path of the feeler. However, the construction can be materially simplified and made more reliable by leaving the rack in a fixed position and shifting the feeler out of the way of the rack, as will now be explained, preparatory to returning the thread guide assembly toward the base chuck.

Shortly after the outer chuck 31 has been retracted and the bobbin dropped, an upstanding roller 81 on the thread guide assembly is engaged by an overhead stationary cam 120 (Fig. 6) which has the effect of moving the thread guide assembly, including the feeler, to the right, toward the chuck 31. The outer or rack-engaging end of the feeler during this movement engages a cam surface 97, shifting the feeler inwardly toward the now vacant axis between the chucks 30 and 31, as shown by comparison of Figs. 6 and 7. So moved, the feeler is now in position to clear the teeth of the tapered portion 78^a of the rack as the thread guide assembly is shifted toward the base chuck by a second stationary overhead cam 310. In the right-hand broken-line position of the feeler 75 in Fig. 8, the thread

guide assembly of which it forms a part is in the act of being shifted by cam 310 toward the base chuck. In the left-hand full-line position of the feeler in Fig. 8, the thread guide assembly is located adjacent to the base chuck 30 with the thread from the inner eye 68 to the discharged full bobbin (not shown) extending across the base chuck in preparation for reception of a new bobbin between the chucks.

The shift of the feeler toward the axis of winding, by cam surface 97, in addition to permitting the feeler to clear the teeth of tapered rack portion 78^a, also positions the inner end of the feeler relatively near to the axis of winding suitably for engagement of the feeler with the initial layers of thread at the beginning of winding on the base portion of the next bobbin.

What is claimed is:

1. A filling winding machine thread guide mechanism including a thread guide having a short quick stroke of traverse and a progressive advance along a rotating winding bobbin, a feeler mounted to travel with the thread guide in its short quick stroke and progressive advance and mounted for movement away from the axis of the bobbin by contact with the wound thread on the bobbin, a profile element cooperating with the feeler to control the progressive advance of the thread guide, a feeler-restoring member for restoring the feeler toward the axis of the bobbin, and a displaceable connection between the feeler and feeler-restoring member permitting withdrawal, away from the axis of the bobbin, of the point of nearest approach of the feeler, as the feeler is moved to greater distances from the axis of the bobbin by contact with the wound thread.

2. A filling winding machine thread guide mechanism including a thread guide having a short quick stroke of traverse and a progressive advance along a rotating winding bobbin, a feeler mounted to travel with the thread guide in its short quick stroke and progressive advance and mounted for movement away from the axis of the bobbin by contact with the wound thread on the bobbin, a profile element cooperating with the feeler to control the progressive advance of the thread guide, a spring for restoring the feeler toward the axis of the bobbin, and a displaceable connection between the feeler and spring permitting withdrawal, away from the axis of the bobbin, of the point of nearest approach of the feeler, as the feeler is moved to greater distances from the axis of the bobbin by contact with the wound thread.

3. A filling winding machine thread guide mechanism including a thread guide having a short quick stroke of traverse and a progressive advance along a rotating winding bobbin, a feeler mounted to travel with the thread guide in its short quick stroke and progressive advance and mounted for movement away from the axis of the bobbin by contact with the wound thread on the bobbin, a profile element cooperating with the feeler to control the progressive advance of the thread guide, a feeler-restoring member for restoring the feeler toward the axis of the bobbin, and a displaceable connection between the feeler and feeler-restoring member, said displaceable connection permitting the feeler to be displaced relatively to the feeler-restoring member upon increase in outward extent of movement of the feeler away from the axis of the bobbin.

4. A filling winding machine thread guide mechanism including a thread guide having a short quick stroke of traverse and a progressive

advance along a rotating winding bobbin, a feeler mounted to travel with the thread guide in its short quick stroke and progressive advance and mounted for movement away from the axis of the bobbin by contact with the wound thread on the bobbin, a profile element cooperating with the feeler to control the progressive advance of the thread guide, a feeler-restoring member having a limited zone of action within which it exerts a restoring action on the feeler tending to restore the feeler toward the axis of the bobbin, and a connection between the feeler and feeler-restoring member permitting displacement of the feeler relatively to the zone of action of the feeler-restoring member while maintaining the feeler under the influence of the feeler-restoring member.

5. A filling winding machine thread guide mechanism including a thread guide having a short quick stroke of traverse and a progressive advance along a rotating winding bobbin, a feeler mounted to travel with the thread guide in its short quick stroke and progressive advance and mounted for movement away from the axis of the bobbin by contact with the wound thread on the bobbin, a profile element cooperating with the feeler to control the progressive advance of the thread guide, a feeler-restoring member having a limited zone of action within which it exerts a restoring action on the feeler tending to restore the feeler toward the axis of the bobbin, and a frictional connection between the feeler and feeler-restoring member permitting displacement of the feeler relatively to the zone of action of the feeler-restoring member while maintaining the feeler under the influence of the feeler-restoring member.

6. A filling winding machine thread guide mechanism including a thread guide having a short quick stroke of traverse and a progressive advance along a rotating winding bobbin, a feeler mounted to travel with the thread guide in its short quick stroke and progressive advance and mounted for movement away from the axis of the bobbin by contact with the wound thread on the bobbin, a profile element shaped for engagement by the feeler at increasing distances of the feeler from the axis of the bobbin as a tapered base portion of thread is wound on the bobbin, a feeler-restoring member for restoring the feeler toward the axis of the bobbin, and a connection between the feeler and feeler-restoring member permitting approximately constant length of return movement of the feeler by the feeler-restoring member notwithstanding increasing distances of the feeler from the axis of the bobbin.

7. A filling winding machine thread guide mechanism including a thread guide having a short quick stroke of traverse and a progressive advance along a rotating winding bobbin, a feeler mounted to travel with the thread guide in its short quick stroke and progressive advance and mounted for movement away from the axis of the bobbin by contact with the wound thread on the bobbin, a profile element cooperating with the feeler to control the progressive advance of the thread guide, the portion of the profile element which determines the shape of the base portion of thread wound on the bobbin being tapered to effect a taper of such base portion, a feeler-restoring member for restoring the feeler toward the axis of the bobbin, and a displaceable connection between the feeler and feeler-restoring member permitting withdrawal, relative to the axis of the bobbin, of the point of nearest ap-

approach of the feeler, as the feeler is progressively moved along the tapered portion of the profile element.

8. A filling winding machine thread guide mechanism including a thread guide having a short quick stroke of traverse and a progressive advance along a rotating winding bobbin, a feeler mounted to travel with the thread guide in its short quick stroke and progressive advance and mounted for movement away from the axis of the bobbin by contact with the wound thread on the bobbin, a profile element cooperating with the feeler to control the progressive advance of the thread guide, the profile element being shaped to condition the advance of the thread guide upon increasingly greater outward movement of the feeler during winding of a tapered base portion of the bobbin and being shaped to provide an approximately cylindrical full-diameter main body portion of thread on the bobbin, a feeler-restoring member for restoring the feeler toward the axis of the bobbin, and a displaceable connection between the feeler and feeler-restoring member permitting withdrawal, relative to the axis of the bobbin, of the point of nearest approach of the feeler, as the feeler is moved to greater distances from the axis of the bobbin by contact with the wound thread.

9. A filling winding machine thread guide mechanism including a thread guide having a short quick stroke of traverse and a progressive advance along a rotating winding bobbin, a feeler mounted to travel with the thread guide in its short quick stroke and progressive advance and mounted for displacement outwardly from the axis of the bobbin by contact with the forming package of thread on the bobbin, a feeler-restoring member for restoring the feeler toward the axis of the bobbin, the feeler-restoring member having limited movement of materially less length than the displacement of the feeler outwardly from the axis of the bobbin, and a connection between the feeler and feeler-restoring member permitting outward shift of the feeler relative to the feeler-restoring member as the feeler progresses along a forming tapered base portion preceding the main body portion of the package, and inward shift of the feeler relative to the feeler-restoring member after winding such main body portion of the package.

10. A filling winding machine thread guide mechanism including a thread guide having a short quick stroke of traverse and a progressive advance along a rotating winding bobbin, a feeler mounted to travel with the thread guide in its short quick stroke and progressive advance and mounted for displacement outwardly from the axis of the bobbin by contact with the forming package of thread on the bobbin, a feeler-restoring member for restoring the feeler toward the axis of the bobbin, the feeler-restoring member having limited movement of materially less length than the displacement of the feeler outwardly from the axis of the bobbin, and a frictional connection between the feeler and feeler-restoring member permitting outward shift of the feeler relative to the feeler-restoring member as the feeler progresses along a forming tapered base portion preceding the main body portion of the package, and inward shift of the feeler relative to the feeler-restoring member after winding such main body portion of the package.

11. A filling winding machine thread guide mechanism including a thread guide having a short quick stroke of traverse and a progressive

advance along a rotating winding bobbin, a feeler mounted to travel with the thread guide in its short quick stroke and progressive advance and mounted for displacement outwardly from the axis of the bobbin by contact with the forming package of thread on the bobbin, a feeler-restoring member for restoring the feeler toward the axis of the bobbin, the feeler-restoring member having limited movement of materially less length than the displacement of the feeler outwardly from the axis of the bobbin, a connection between the feeler and the feeler-restoring member permitting relative shift between the feeler and the feeler-restoring member, a profile element engageable with the feeler and shaped to permit outward shift of the feeler relative to the feeler-restoring member during a portion of the winding of the package, and mechanism for shifting the feeler inwardly relative to the feeler-restoring member following winding of the main body portion of the package.

12. A filling winding machine thread guide mechanism including a thread guide having a short quick stroke of traverse and a progressive advance along a rotating winding bobbin, a feeler mounted to travel with the thread guide in its short quick stroke and progressive advance and mounted for displacement outwardly from the axis of the bobbin by contact with the forming package of thread on the bobbin, a feeler-restoring member for restoring the feeler toward the axis of the bobbin, the feeler-restoring member having limited movement of materially less length than the displacement of the feeler outwardly from the axis of the bobbin, a connection between the feeler and the feeler-restoring member permitting relative shift between the feeler and the feeler-restoring member, a profile element engageable with the feeler and shaped to permit outward shift of the feeler relative to the feeler-restoring member during a portion of the winding of the package, and a cam cooperating with the feeler to shift the feeler inwardly relative to the feeler-restoring member following winding of the main body portion of the package.

13. An automatic filling winding machine including a thread guide having a short quick stroke of traverse and a progressive advance along a rotating winding bobbin, a feeler mounted to travel with the thread guide in its short, quick stroke and progressive advance and mounted for displacement outwardly from the axis of the bobbin by contact with the forming package of thread on the bobbin, a profile element including a tapered portion controlling outward displacement of the feeler during said progressive advance, a feeler-restoring member for restoring the feeler toward the axis of the bobbin, the feeler-restoring member having limited movement of materially less length than the displacement of the feeler outwardly from the axis of the bobbin, mechanism for causing a return movement of the thread guide and its feeler in the direction opposite to said progressive advance following winding of the package on the bobbin, and mechanism for shifting the feeler inwardly relatively to the feeler-restoring member to permit the feeler to clear the tapered portion of the profile element in said return movement of the thread guide and feeler.

14. An automatic filling winding machine including a thread guide having a short quick stroke of traverse and a progressive advance along a rotating winding bobbin, a feeler mounted to travel with the thread guide in its short

quick stroke and progressive advance and mounted for displacement outwardly from the axis of the bobbin by contact with the forming package of thread on the bobbin, a profile element including a tapered portion controlling outward displacement of the feeler during said progressive advance, a feeler-restoring member for restoring the feeler toward the axis of the bobbin, the feeler-restoring member having limited movement of materially less length than the displacement of the feeler outwardly from the axis of the bobbin, mechanism for causing a return movement of the thread guide and its feeler in the

direction opposite to said progressive advance following winding of the package on the bobbin, and a cam cooperating with the feeler to shift the feeler inwardly relatively to the feeler-restoring member to permit the feeler to clear the tapered portion of the profile element in said return movement of the thread guide and feeler.
